(57) **CLAIM**

The ornamental design for a tool handle, as shown and described.

DESCRIPTION

FIG. 1 is a perspective view of an embodiment of a tool handle embodying our design;

FIG. 2 is a front view of the tool handle of FIG. 1;

FIG. 3 is a rear view of the tool handle of FIG. 1;

FIG. 4 is a first side view of the tool handle of FIG. 1;

FIG. 5 is a second side view of the tool handle of FIG. 1;

FIG. 6 is a top view of the tool handle of FIG. 1; and,

FIG. 7 is a bottom view of the tool handle of FIG. 1.

The broken lines form no part of the claimed design.
